UNITED STATES PATENT OFFICE

123,837

DESIGN FOR A FLASHLIGHT FOR LADIES' PURSES

Leo Hammerschmidt, St. Louis, Mo.

Application June 21, 1940, Serial No. 93,178

Term of patent 7 years

To all whom it may concern:

Be it known that I, Leo Hammerschmidt, a citizen of the United States, residing at 3916 Minnesota Ave., in the county of St. Louis and State of Missouri, have invented a new, original, and ornamental Design for a Flashlight for Ladies' Purses, of which the following is a specification, reference being had to the accompanying drawing, forming part thereof.

Fig. 1 is a perspective view of the flashlight for ladies' purses, showing my new design.

Fig. 2 is a top plan view thereof, and

Fig. 3 is an end elevational view of the same.

I claim:

The ornamental design for a flashlight for ladies' purses, as shown.

LEO HAMMERSCHMIDT.
